UNITED STATES PATENT OFFICE.

ELSWORTH E. QUAINSTANCE, OF LOS ANGELES, CALIFORNIA.

PERMUTATION LOCK.

Application filed December 26, 1924. Serial No. 757,989.

My present invention being referred to as a permutation lock, it may be understood to be an object of this invention to provide a simple, reliable and effective lock requiring no key; and it is an especial object of this invention to provide an improved lock of the general type referred to whose principles are capable of very wide application, being suitable for embodiment not only in door locks, as hereinafter specifically described by way of illustration, but in pad locks and other locks either permanently incorporated in larger structures or adapted to be sold and used as separate articles.

It is an object of this invention to provide a permutation lock, which may, in many respects, resemble locks heretofore patented by me, such as, for example, the lock disclosed in my Patent No. 1,238,435 granted 15 August 28th, 1917, but in which the parts are comparatively few in number and are, for the most part, adapted to be made from sheet metal or tubular or other inexpensive stock, although capable of being organized 20 to produce a substantially fool-proof and tamper-proof lock.

It is a further object of this invention to provide a permutation lock comprising fluted tumblers exposed for manual manipulation and adapted to be assembled into an organization which may be superficially resemble a door handle or a drawer pull, the mentioned tumblers being preferably provided with stop discs variably inserted there- 25 in and so related to one another and to cooperating parts that, to unlock the same all tumblers may rotate in the same direction with reference to an arbitrary zero.

It is a further object of this invention to provide a permutation lock which can be opened even in the dark by any person informed as to the correct key or combination number and possessed of normal hearing, audible means being provided to indicate 45 the extent of movement of each tumbler.

It is a further object of this invention as the same may be embodied in a door lock, or the like, to provide an organization enabling a door to be opened at will from the interior, although preventing unauthorized opening of the same from the outside; and a preferred embodiment of my invention may also comprise means rendering it entirely impracticable for an unauthorized person, by reliance upon any usual lock

picking methods, such as various applications of pressure and a careful attention to sounds, to open my lock by any means short of a systematic trial of numbers within the limits of its range. This range may ordinarily be 9999; but it may be any desired smaller or larger number.

Other objects and advantages of my invention will appear from the following description of a preferred embodiment thereof, taken in connection with the appended claims and the accompanying drawings, in which—

Fig. 1 may be regarded as a horizontal sectional view through the edge of a door 70 to which an embodiment of my invention is applied.

Fig. 2 is a detail elevational view taken substantially as indicated by the line 2—2 of Fig. 1.

Fig. 3 is an elevational view, with parts broken away, taken substantially as indicated by the arrow 3 of Fig. 1, and on a larger scale than said figure.

Fig. 4 is a detail view taken substantially as indicated by the line 4—4 of Fig. 3.

Fig. 5 is a view taken in the plane indicated by the line 5—5 of Fig. 3, showing only a split ring hereinafter referred to.

Fig. 6 is a sectional view taken as indicated by the line 6—6 of Fig. 5.

Fig. 7 is a substantially central vertical section through a lock of the character shown in the preceding figures, this view 90 being taken as indicated by the line 7—7 of Fig. 1.

Figs. 8, 9 and 10 are respectively horizontal sectional views taken as indicated by the lines 8—8, 9—9 and 10—10 of Fig. 7.

Referring to the details of that specific form of my invention chosen for purposes of illustration, 11 may be the body of a door, and 12 may be a latch organization of any usual or preferred character, such as, for example, an organization comprising a sliding latch bolt 13, with which a pivoted element 13', or the like may optionally be associated, said latch bolt being movable either by means of a usual square shaft 14, to which knobs 15, 15' are shown as connected, or by any means engaging a plate 16, or its equivalent, shown as projecting rearwardly through the housing of the mentioned latch organization.

The form of my invention herein specifically described being directed to a control of a latch bolt which is dependent upon the longitudinal movement of the plate 16, or its equivalent, I may provide said plate with means such as a slot 17, adapted to receive a transversely extending main bolt 18, the latter being shown as provided with means for retaining said plate, and thereby the sliding bolt 13, in its advanced position. For example, in order to accomplish the results referred to, and at the same time facilitate the opening of a door from the interior, I may provide the bolt 18, or its equivalent, with means such as a sleeve 19, shown as rotatable thereon but longitudinally movable thereby (as by the engagement of a screw 20, entering a slot 21), the inner end of this sleeve carrying means such as a dog 22, to engage a stop 23, or its equivalent, on said plate; and the outer end of said sleeve being provided with means, such as a knurled handle or milled head 24 (which may carry a pointer 25, to indicate the position to which the same is adjusted) for independently rotating said sleeve and dog from its operative position to the inoperative position shown in dotted lines in Fig. 2.

By the means described, or by equivalent means, the plate 16, or any element operatively connected with a latch, may be released in either of two ways: By rotation of the head or handle 24, the plate 16 may be released from the interior of a room, lifting of dog 22 permitting the door to be opened upon the rotation of either of the knobs, 15, 15'; but its release from the outside may be conditional upon an outward movement of the bolt 18, whereby the dog 22, or its equivalent, may be advanced out of the plane of the stop 23, substantially as indicated in dotted lines in Fig. 7.

And this outward movement of the bolt 18, or its equivalent, whether or not the same is employed directly as a latch element, may depend upon the proper manipulation of a lock comprising fixed spindles, split rings splined thereon, and movable tumblers and pallets associated substantially as hereinafter described.

One side of a door, as the side 27 thereof, I may provide a permutation lock organization comprising a pair of rounded heads or end elements 28, 28' between and into which may extend a hollow core or spindle 29, this core being shown as pinned at 30 to one of said heads, and both of said heads being shown as secured by relatively inaccessible cap nuts on the ends of threaded pins or stud bolts 31, 31' extending through the door 11, and also through plates 32, 32' optionally interposed on the respective faces of the door 11. The spindle 29 may be provided, as best shown in Figs. 8, 9 and 10, with a

longitudinal channel 33 adapted to interfit with projections 34 provided on or in each of a plurality of split rings 35, (see Figs. 5, 6 and 7) splined theron and interposed as hereinafter described. It may be regarded as immaterial which of the mentioned parts carries a projection, extending into a channel in the other, and the parts referred to, or their equivalents, may constitute the only stationary elements in the external portions of my novel lock; although I show the same as associated with a pair of co-operating spacing collars 36, 36' at the upper end of the spindle 29, and with an inverted lower spacing collar 37, below which I may optionally insert a pin 38. This pin, if used, may serve only to facilitate assembly and to obviate danger of a scattering of parts at such times as my lock may be taken partially apart, as for the purpose of changing the combination thereof, at which times only one of the heads or end elements, as the lower end element 28' need be separated from the spindle 29.

It will be noted that one or both of the upper spacing collars 36, 36' are slotted, as at 38^a and 38^b of Fig. 4, and that the spindle 29 is preferably slotted, as between 38^c and 38^d, Fig. 7, to permit a limited lateral sliding movement of the bolt 18, or its equivalent, with which one or more pallets are rigidly connected, a cylindrical end 39 of what I herein term a true or primary pallet 40 being shown as rigidly secured to the bolt 18 by a pin 41, and the corresponding end of what I herein term a false or secondary pallet 42, extending parallel with said true pallet being expanded at its upper end and provided with two cylindrical terminal portions 43, 43', by which this pallet is sleeved on said bolt in such manner as to permit the interposition of, for example, a compression spring 44, normally holding the upper cylindrical portion 43 of one pallet in contact with the cylindrical end 39 of the other. This construction yieldably retains the respective pallets in the relative positions in which they are shown in solid lines in Figs. 1, 7, 9 and 10, although permitting the respective pallets, and thereby the bolt 18, to advance whenever the combination of my lock is successfully worked, as by a proper positioning of tumblers, such as are hereinafter described.

For the purpose last referred to, I may use tumblers of any preferred type; but I consider it especially advantageous to employ, in conjunction with the parts above mentioned, or their equivalents, tumblers substantially such as are shown at T¹, T², T³ and T⁴, in Fig. 7, with which Figs. 8, 9 and 10 may be compared, each tumbler comprising a substantially uniform cup 45, these cups being economically cut and shaped from sheet metal, or the like, in

such manner that each is provided with ten circumferential depressions 46 separated by an equal number of ridges 47. Each cup may optionally be provided at or near the bottom thereof with a milled area or edge 48; and each may be provided in its bottom with a substantially circular aperture 49 of such size as to permit it to rotate freely upon the spindle 29, or its equivalent.

10 No numbers need appear on the exterior of my tumblers or upon other parts of my lock; and, when numbers, letters, or the like, are interiorly provided, instead of displaying the same directly in the cups 45, or 15 their equivalents, I prefer to provide each cup with a correspondingly fluted false bottom or "number" or "character" plate 50 (see Fig. 8). This bottom or number plate may optionally be spaced from the bottom 20 51 of each cup by means such as a ring 52; and the mentioned false bottoms, like the mentioned cups, may all be substantially identical, adapting them to be inserted at random in the respective cups, each false 25 bottom plate being provided with numbers from zero to 9 and with a single notch, such as the notch 53, shown as positioned between the numbers 5 and 6, into which notch the pallets 40 and 42, or their equivalents, 30 may advance only when a tumbler comprising the mentioned cup and bottom plate are suitably oriented.

Above each of the mentioned number plates and directly contacting with the same 35 I may insert stop discs 54, fluted similarly to the mentioned plates and each provided with a single stop pin 55 and with slots or notches 56, any one of these slots or notches being capable of coincidence with the notches 53 in the plates 50, or their equivalents, the angle at which the respective stop devices are set within the respective cups 45 being intended to predetermine a combination number. The mentioned split rings 40 35, one of these rings being positioned above each stop disc 54, may be provided with not only uniform fixed stops 57, projecting outwardly into the path of the mentioned stops 55, adapted to be variously oriented within the respective tumblers, but with pairs of balls 58, or their equivalents, these balls being shown as held within, although slightly protruding from, cavities 59, containing springs 60. The construction here referred 45 50 55 to is preferably such that the fixed split rings 35 serve not only to provide fixed stops for the respective tumblers, and to provide guide passages between which the pallets may be advanced, (see Fig. 10) but also as spacers pressed by the springs 60, or their equivalents, into sliding engagement with the bottoms of the superimposed cups of a series of tumblers; and the balls 58, or their equivalents, may serve not only 60 65 as bearings and as pressure-transmitting

means, but also as means for yieldably retaining each tumbler in its adjusted position; and also as means for producing a "click" of which one manipulating the combination may receive auditory information as to the extent of movement of a tumbler from an initial or known position.

Now, it will be obvious that if all the stop discs 54 were inserted with their stops 55 directly above the 9's, of the respective number plates 50 (i. e. in the positions in which these elements are shown in full lines in Fig. 10) then the lock so adjusted could be opened upon a turning of all the tumblers as far as possible to the left (in the direction of the arrow 62) until the stops 55 contact with the fixed stops 57. The key number or combination of a lock so set would obviously be "9999"; but if, for example, the stop plate of the uppermost tumbler T^1 were so inserted as to bring its stop pin immediately above the "eight" of Fig. 8 (i. e. in the position 55^a of Fig. 10) and if the stop plate of the next lower tumbler T^2 were so inserted as to bring its stop pin immediately above the "seven" of its number plate 50 (i. e. in the position 55^b of Fig. 10) then obviously the key number of the resultant combination, assuming no change in the setting of the tumblers T^3 and T^4 , would be "8799"—these being mere examples of the method of setting my permutation lock to any desired number between "0000" and "9999".

It will be appreciated that, in the organization described, a rotation of any tumbler as far as it will go in the direction of the arrows 62 (in an "unscrewing" direction) is effective to carry a tumbler to "9" and an opposite movement is effective to carry a tumbler to "0". To reach such numbers as, for example, "3", "5", "7", after the tumblers have been disarranged to prevent an unlocking, it will be obvious that the most expeditious course may involve a turning of all tumblers to "9" or to "0", after which the respective tumblers may be returned two or more steps, as required; and, among the important advantages of the described construction, I may emphasize the facts that all of the mentioned tumblers are formed from similar units, all numbers reading in the same direction, and the mere click of the balls 58, 58', as they enter one after another of the radial slots 56, may be utilized and relied on to give accurate information as to the movement and consequent position of any tumbler.

It will be understood that when the tumblers are all aligned so that the notches 53 in the bottom plates 50 lie in the same plane with the openings of the fixed split rings 35, the mentioned pallet or pallets connected with the bolt 18 may be drawn forward or outward, as by means such as a

handle or knob 63. This handle or knob is preferably secured directly only to the end 43 of the pallet 42. Assuming the indicated alignment of parts, the movement of this handle substantially to the position shown in dotted lines in Fig. 7 (with the result indicated in dotted lines in Fig. 10) may be effective to disengage the dog 22 on the shaft 18 from contact with the stop 23 on the plate 16, thereby enabling the door 11 to be opened by the turning of the knob 15, or by equivalent means.

In order that no unauthorized manipulation of the bolt 18, or its equivalent, shall be of the slightest avail in enabling even a lock expert to tamper with and open a lock of the general character described, without knowing its combination or trying successive numbers systematically, I consider it advantageous not only to connect a pair of pallets by resilient means such as the spring 44, but to provide one of these pallets, as the false pallet 42, with notches of sufficient depth and diameter not only to clear at all times the bottoms 51 of the respective cups 45, but to clear also the number plates 50, regardless of the orientation thereof, and to enter whatever slots 56, in the stop discs 54, may happen to lie opposite the openings in the split rings 35. Thus, any premature pull upon the knob 63, or its equivalent, may cause the false pallet 42, or its equivalent, to part company with the true pallet 40 and to advance into substantially the position in which it is shown in solid lines in Fig. 3,—so that its teeth or projections 42', entering both the slots 56 in the stop plates 54 and the fixed openings in the split rings 35, may effectively prevent the rotation of any tumbler until the tampering operator shall release the knob 63. When, however, the tumblers have been turned to their respective proper positions, permitting not only the pallet 42 but the true pallet 40, (the latter having narrower notches between teeth 40') to be advanced, (these teeth 40' being, in the organization described, capable of advancing only when the slots 53 in the number plates 50 are turned opposite the same) the outward pressure applied to the true pallet 40 by way of the spring 44 is effective, whenever the knob 63 is drawn outward, to advance the said number pallet 40, and thereby the bolt 18, or its equivalent, substantially to the position indicated in dotted lines in Fig. 7.

In the ordinary use of my lock, in the described embodiment thereof applicable to a house door, or the like, it will be evident that, by simply turning the knob 24 into such a position as to hold the dog 22 from engagement with the stop 23 on the plate 16, the door latch bolt 13, or its equivalent may be exempted from control by my described permutation lock, as may be desirable during

the ordinary daylight hours. At nightfall, or whenever desired, the knob 24 being so turned as to throw the dog 22 into the position in which it is shown in solid lines in Fig. 2, the latch bolt 13, or its equivalent, 70 may however be subjected to control by the said permutation lock; but any effort to tamper with said lock by a premature pull upon the handle 63, or its equivalent, must absolutely defeat its own purpose, by rendering the rotative manipulation of the described tumblers impossible, until said handle shall be released. Anyone desiring to lock his door, may, instead of completely disarranging the tumblers, merely rotate 80 any selected tumbler, as the tumbler T², through a predetermined distance in either direction, or sufficiently to produce a predetermined number of clicks; and, when he thereafter desires to unlock the same, he may similarly restore the mentioned tumbler to its initial unlocking position. If, when this is done, the pallets fail to respond to a pull upon the handle 63, or its equivalent, he may be therefore satisfied that, in his absence, 90 some effort has been made to unlock the door. In this case, he may slightly rotate all tumblers to "0" or to "9", thereafter restoring each of them separately to the 95 unlocking position required by the previous setting of the combination. When the combination is, for any reason, to be changed, the lower end element 28', or its equivalent, may be removed, the pin 23, if employed, 100 may be withdrawn, and one or more of the tumblers may be reset by any desired change in the orientation of a stop plate 54 therein, the parts being then reassembled and presenting exactly the same external appearance as before. This appearance may be 105 distinctly ornamental, and the exposed parts may not only be formed of a non-corrosive metal, but nickel-plated or otherwise attractively finished; and the external portions of my assembled permutation lock may have the general appearance, and optionally also the function, of a handle fixed to a 110 door.

Although I have herein described my invention in a preferred form, I am aware 115 that various changes and modifications may be made by those skilled in the art to which this case relates, without the slightest departure from the spirit and scope of my invention, as the same is indicated above and in the following claims.

I claim as my invention:

1. A permutation lock comprising: a relatively fixed spindle; a bolt movable transversely thereof; a pallet connected with said bolt and movable through a longitudinal slot in said spindle; spacing elements comprising fixed stops on said spindle; and separate tumblers surrounding said spindle, each comprising a cup which is provided 130

- with a peripheral wall of substantially uniform thickness, fluted to receive internal members correspondingly fluted.
2. A lock organization as defined in claim 5 in which said tumblers all comprise substantially identical means whereby their rotation in the same direction brings them all toward their respective zeros.
3. A lock organization comprising external and manually movable tumblers each comprising: a fluted cup containing a correspondingly fluted and interfitting character plate insertable therein as a false bottom and rotatable therewith.
- 10 4. A lock organization comprising external and manually movable tumblers each comprising: a fluted cup containing a correspondingly fluted and interfitting character plate insertable therein as a false bottom and rotatable therewith, each plate being provided with a single radial notch into which, upon suitable positioning of said tumbler, a pallet may be advanced.
- 15 5. A lock organization comprising external and manually movable tumblers each comprising: a fluted cup containing a character plate therein as a false bottom and rotatable therewith, and a stop plate correspondingly fluted to interfit therewith and adapted to be variously inserted with reference to said character plate.
- 20 6. A lock organization comprising: a spindle carrying exposed tumblers which include substantially uniform cups; and fixed stop means in each cup in the form of a solid split ring held against rotation on said spindle.
- 25 7. A lock organization comprising: a spindle carrying exposed tumblers which include substantially uniform cups; and fixed stop means in each cup in the form of a solid split ring held against rotation on said spindle and provided with a ball bearing.
- 30 8. A lock organization comprising a spindle carrying exposed tumblers which include substantially uniform cups; and fixed stop means in each cup in the form of a solid split ring held against rotation on said spindle and provided with a ball bearing, each of said split rings being provided with a radially projecting stop adapted to engage a co-operating stop which is adapted to be variously positioned within a cup.
- 35 9. A lock organization comprising: a spindle carrying exposed tumblers which include substantially uniform cups; a single stop plate, in each cup and fixed stop means in each cup in the form of a solid split ring held against rotation on said spindle and provided with means for yieldably retaining the same in any of a plurality of adjusted positions, by engagement with said single stop plate.
- 40 10. In a permutation lock comprising tumblers mounted on a spindle and exposed to manual manipulation, a set of tumblers each comprising a fluted cup and a correspondingly fluted stop plate variously insertable therein.
- 45 11. In a permutation lock comprising tumblers mounted on a spindle and exposed to manual manipulation, a set of tumblers each comprising a fluted cup, a number plate, and a correspondingly fluted stop plate variously insertable therein with reference to said number plate, the latter being provided with a single radial slot.
- 50 12. In a permutation lock comprising tumblers mounted on a spindle and exposed to manual manipulation, a set of tumblers each comprising a fluted cup and a correspondingly fluted stop plate variously insertable therein with reference to a number plate provided with a single radial slot, said number plate being spaced from the bottom of said cup.
- 55 13. In a permutation lock comprising tumblers mounted on a spindle and exposed to manual manipulation, a set of tumblers each comprising a fluted cup and a correspondingly fluted stop plate variously insertable therein with reference to a number plate provided with a single radial slot, said number plate being spaced from the bottom of said cup.
- 60 14. In a permutation lock comprising tumblers mounted on a spindle and exposed to manual manipulation, pallets extending longitudinally of said spindle, and a set of tumblers each comprising a fluted cup and a correspondingly fluted stop plate variously insertable therein, said cups being spaced by means comprising split rings provided with fixed stops.
- 65 15. A permutation lock comprising: a spindle; tumblers rotatable thereon; a bolt laterally movable with reference to said spindle; a plurality of pallets also movable laterally of said spindle; means for rigidly connecting one of said pallets directly with said bolt and a resilient connection between said pallets.
- 70 16. A permutation lock comprising: a spindle; tumblers rotatable thereon; a bolt laterally movable with reference to said spindle; a plurality of pallets also movable laterally of said spindle; means for rigidly connecting one of said pallets directly with said bolt; and resilient means whereby a pull upon another of said pallets may impart movement to said first mentioned pallet and to said bolt when said tumblers are turned to their respective unlocking positions.
- 75 17. A permutation lock comprising tumblers and a true pallet and a false pallet resiliently connected.
- 80 18. A permutation lock comprising cups

containing spacing elements in the form of solid split rings, each provided with ball bearings resiliently pressed outward through one surface thereof, one surface of each ring being incidentally pressed toward the bottom of an adjacent cup.

19. A permutation lock comprising tumblers including cups having walls of substantially uniform thickness, cut and shaped from sheet metal and fluted to facilitate

manual manipulation and to receive variously insertable stop plates correspondingly fluted, said cups being all substantially identical and disposed with their bottoms in the same direction.

In testimony whereof, I have hereunto set my hand at Los Angeles, California, this 18th day of December, 1924.

ELSWORTH E. QUAINSTANCE.
